[57] CLAIM

The ornamental design for a combined head and handle assembly for a tank-type garden sprayer, as shown and described.

DESCRIPTION

FIG. 1 is a top plan view of a combined head and handle assembly for a tank-type garden sprayer;

FIG. 2 is a front elevational view thereof;

FIG. 3 is a side elevational view thereof, the side opposite being a mirror image;

FIG. 4 is a rear elevational view thereof; and

FIG. 5 is a bottom plan view thereof.

The broken line showing of the tank in FIGS. 1-5 is for illustrative purposes only and forms no part of the claimed design.

FIG. 1

FIG. 2

FIG. 3

FIG. 4

FIG. 5
